UNITED STATES PATENT OFFICE.

ALFRED THEODORE LAINSON, OF COUNCIL BLUFFS, IOWA, ASSIGNOR OF ONE-HALF TO E. C. LAINSON, OF SAME PLACE.

NON-REFILLABLE BOTTLE.

SPECIFICATION forming part of Letters Patent No. 597,117, dated January 11, 1898.

Application filed March 16, 1897. Serial No. 627,780. (No model.)

To all whom it may concern:

Be it known that I, ALFRED THEODORE LAINSON, a citizen of the United States, residing at Council Bluffs, in the county of Pottawattamie and State of Iowa, have invented 5 a new and useful Non-Refillable Bottle, of which the following is a specification.

The invention relates to improvements in non-refillable bottles.

10 The object of the present invention is to improve the construction of non-refillable bottles and to provide a simple and comparatively inexpensive one which will have to be sufficiently mutilated in order to obtain access to its contents to prevent it from being 15 afterward used and sold as an original package, thereby insuring purchasers and proprietors against fraudulent refilling and adulteration.

20 A further object of the invention is to provide a simple, inexpensive, and efficient device for enabling the neck of the bottle to be readily severed from the body thereof in order that the bottle may be mutilated without 25 breaking the neck into small fragments.

Another object of the invention is to provide means whereby the neck of the bottle, after it has been severed from the body of the same, will be connected therewith in order 30 that persons using the contents of the bottle may see at a glance that it is genuine.

The invention consists in the construction and novel combination and arrangement of parts, as hereinafter fully described, illustrated in the drawings, and pointed out in 35 the claims hereto appended.

In the drawings, Figure 1 is a perspective view of a non-refillable bottle constructed in accordance with this invention. Fig. 2 is a 40 central vertical sectional view of the upper portion of the bottle. Fig. 3 is a detail perspective view of the rotary frame which carries the glass-cutter.

Like numerals of reference designate corresponding parts in the several figures of the drawings.

1 designates a bottle provided with upper and lower corks or stoppers 2 and 3, arranged at the top and bottom of the neck of the bottle, and the lower cork 3 is provided with a

metal plate 4, which covers its upper face and which engages the lower one of a series of annular shoulders 5 of the neck of the bottle. The annular shoulders 5, which are arranged at regular intervals and which may be of any desired number, are formed by recessing the inner face of the neck, as shown, and the lower cork, which may be readily forced downward past the shoulders, is prevented by the same from being withdrawn. 55 The plate 4, which may be constructed of zinc or any other suitable metal, prevents a corkscrew from penetrating the lower cork, and forms an efficient shield for the same.

In order to obtain access to the lower cork 65 and the contents of the bottle, the neck thereof must be broken off, and to facilitate ready breakage the neck is provided, below the upper face of the lower cork, with a thin connecting ligament 6, which renders the neck 70 frangible and which is formed by an exterior groove V-shaped in cross-section.

The neck is provided, above and below the frangible ligament 6, with shallow exterior grooves 7, receiving upper and lower rings 8 75 of a rotary frame 9, which is provided with a finger-loop 10 and which is preferably constructed of wire. The upper and lower loops, which are connected by a cross-piece, carries a steel glass-cutter 11, arranged to engage 80 the reduced portion or ligament 6 of the neck, so that by rotating the frame 9 the cutter is caused to cut into the ligament or reduced portion. After the bottle has been cut by the glass-cutter the neck is readily separated 85 from the body of the bottle by a light blow, and, as the line of severance is below the plate 4, the lower cork is freed and the neck is connected to the body of the bottle by the rotary frame as the cut is made between the upper 90 and lower rings. The severed neck identifies the body of the bottle and tells at a glance that the contents are genuine.

It will be seen that the bottle is exceedingly simple and inexpensive in construction, 95 that it is absolutely impossible to obtain access to its contents until it is sufficiently mutilated to destroy its identity and to prevent it from being afterward used and sold as an original package, and that it will guar- 100

guarantee to purchasers that its contents are genuine and unadulterated. What I claim is—

1. In a non-refillable bottle, the combination of a bottle provided with a frangible ligament, and a rotary frame connected with the bottle above and below the ligament and carrying a cutter arranged to engage the said ligament to enable the neck to be readily severed from the body of the bottle, said rotary frame serving to connect the neck to the body of the bottle after the former has been severed from the latter, substantially as described.

15 2. In a non-refillable bottle, the combination of a bottle provided with a frangible ligament and having grooves above and below the same, a rotary frame provided with upper and lower rings engaging the said grooves and located above and below the ligament, said frame being provided with a suitable handle, and a cutter carried by the rotary frame and engaging the ligament, substantially as and for the purpose described.

In testimony that I claim the foregoing as my own I have hereto affixed my signature in the presence of two witnesses.

ALFRED THEODORE LAINSON.
